UNITED STATES PATENT OFFICE.

LEOPOLD R. STRAUS, OF NEW YORK, N. Y.

DESIGN FOR A FINGER-RING.

49,974.

Specification for Design.

Patented Nov. 28, 1916.

Application filed September 13, 1916. Serial No. 119,989. Term of patent 7 years.

To all whom it may concern:

Be it known that I, LEOPOLD R. STRAUS, a citizen of the United States, residing in the borough of Manhattan, city, county, and State of New York, have invented a new, original, and ornamental Design for Finger-Rings, of which the following is a specification, reference being had to the accompanying drawing, forming part thereof.

In the drawings, Figure 1, is a perspective view of a finger ring illustrating my

new design. Fig. 2, is a side elevation; Fig. 3, is a side elevation taken at right angles to Fig. 2; and Fig. 4, a top or end view.

I claim:

The ornamental design for a finger ring, as shown.

LEOPOLD R. STRAUS.

Witnesses:

GEO. WM. MIATT,
DOROTHY MIATT.
